[57] CLAIM

The ornamental design for a mold, as shown and described.

DESCRIPTION

FIG. 1 is a perspective view of a first embodiment of the mold of our new design.

FIG. 2 is a end elevational view of the mold of FIG. 1, the opposite end view being identical;

FIG. 3 is a side elevational view of the mold of FIG. 1, the opposite side view being identical;

FIG. 4 is a top plan view of the mold of FIG. 1;

FIG. 5 is a bottom plan view of the mold of FIG. 1;

FIG. 6 is a perspective view of a second embodiment of the mold of our new design;

FIG. 7 is a end elevational view of the mold of FIG. 6, the opposite end view being identical;

FIG. 8 is a side elevational view of the mold of FIG. 6, the opposite side view being identical;

FIG. 9 is a top plan view of the mold of FIG. 6; and,

FIG. 10 is a bottom plan view of the mold of FIG. 6.
